UNITED STATES PATENT OFFICE.

ARNOLD RÜHR, OF BERLIN, GERMANY, ASSIGNOR TO INTERNATIONAL COMBUSTION ENGINEERING CORPORATION, OF NEW YORK, N. Y., A CORPORATION OF DELAWARE.

BOILER FURNACE.

Application filed January 5, 1926, Serial No. 79,279, and in Germany September 21, 1925.

This invention relates to boiler-furnaces, and more especially to that type of furnace in which the combustion space is very largely defined by boiler tubes subject to radiant heat. 5 the invention being particularly useful in connection with stationary boiler installations burning pulverized coal.

It has heretofore been proposed in such pulverized coal burning installations to arrange water screens within the combustion chamber, such water walls or screens being composed of a plurality of boiler tubes or tubes connected into the circulation of the boiler. These have been employed on the 15 side walls; the rear walls; above the ash pit, and elsewhere.

In accordance with the present invention, I propose to insure more effective and better circulation through such elements, while, at 20 the same time, dispensing with any special means for enforcing circulation.

I accomplish the foregoing, together with such other objects as may hereinafter appear, or are incident to my invention, by 25 means of a construction which I have illustrated in the preferred form in the accompanying drawings, wherein—

Fig. 1 is a fragmentary vertical section through a boiler-furnace embodying my 30 improvements, and

Fig. 2 is a transverse vertical section through one-half of the boiler-furnace shown in Fig. 1.

Referring now to the drawings, the reference character A denotes the combustion chamber which has an outlet throat 7 at its upper part, the pulverized coal being admitted downwardly into the upper part of the combustion chamber through the arch 40 8 by means of a row of suitable burners 9, the fuel and flame stream taking a U-shape course through the combustion chamber, with combustion completed before the first pass of the main boiler B is reached. A portion of 45 the air for combustion is admitted through the burners, and the balance is admitted through rows of air inlets 10 located at successive levels in the front wall 11, which is preferably made hollow, so that the combustion air admitted through the inlets 10 is heated in traversing the space within the front wall. In front of the rear wall 12 of the combustion chamber is a water wall 13 composed of comparatively closely spaced 50 tubes 18, the upper ends of which are con-

nected into the lower or mud drum 14 of the boiler. These tubes are preferably small in diameter, so as not to weaken the drum structure. Pairs of the tubes 18 are connected at their lower ends into junction blocks 15. 60

Above the ash pit C of the combustion chamber is the water screen b, such screen being composed of tubes 16 spaced well apart to permit the refuse particles gravitating out of the fuel and flame stream to freely 65 pass to the ash pit, such particles being thereby cooled below the melting point in order that the refuse particles may deposit in the ash pit in readily removable form.

The upper ends of the tubes 16 are connected into the junction boxes 15, and the lower ends of the tubes 16 are connected into the header 17, this header being preferably divided by a division plate 17^a into two halves as indicated in dot and dash lines in Fig. 2. A pair of tubes 18 connect each half of the header 17 with the mud drum 14, such tubes 18 constituting downcomers and being preferably somewhat larger in diameter than the tubes 16, which latter, in turn, are larger 80 in diameter than the tubes 18.

By this arrangement the water screen and the rear water wall a have local circulation therethrough, although they are connected into the main boiler. It will also be seen 85 that the water screen and the water wall a are divided into two units or groups of equal number by tubes. This insures a more uniform circulation through all of the tubes, and overcomes one of the difficulties heretofore encountered in this art. At the same time, the arrangement is such as to insure rapid and unrestricted circulation through the water screen and the water wall, and to insure that the circulation shall always be upwardly 90 therethrough, in which connection it has sometimes been found that the circulation in the usual arrangements employed ceases temporarily and even reverses. This is overcome by the downcomer connections 18 which are exterior of the combustion chamber, and which provide the local circulation hereinbefore referred to.

Coming now to the screens or water walls for the side walls of the combustion chamber, it will be seen that I have divided this into two units d, e, there being preferably two such units, each of which is composed of small tubes 19. The tubes of each unit pass outwardly for connection into the headers 20, 20, 105 110

at the top, and 21, 21, at the bottom. A down-comer 22 connects each of the lower headers 21 to the mud drum 14, and an upcomer 23 connects each of the headers 20 to the header 24, which, in turn, is connected by a multiplicity of small pipes 25 to one of the upper drums of the boiler, this being done to prevent weakening of the drum structure, and to assist in securing an equalizing effect as between the two units on each side wall of the combustion chamber. The pipes 22 compare in size with the pipes 18, as do the pipes 23, and the pipes 19 compare in size with the pipes 13.

15. Thus, it will be seen that each unit has its own independent circulation, and that by splitting the side water walls into these units, there is a tendency to secure more uniform circulation therethrough, this end being also furthered by having the pipes 23 empty into the header 24, as above set forth. For reasons already pointed out in connection with the other units described, there will always be more effective and constantly upward flow 25 through the units *d*, *e*, of each side water wall. These results are further ensured by the fact that I connect the headers 20 and 21 by means of tubes 19^a of which there are a pair connecting each pair of headers, such tubes lying exterior of the furnace and constituting down-comers. By virtue of the local circulation thus made possible, flow through the down-comers 22 is assisted.

30. In order to prevent weakening of the drum structure 14, I prefer to connect the pipes 18 and 22 to headers 26, which, in turn, are connected to the drum 14 by a plurality of small pipes 27.

I claim:—

40. 1. In combination, a boiler having upper drums and a lower mud drum and interconnecting tubes, a combustion chamber, a tubular screen for an upright wall thereof, the tubes of which are divided into groups, upper 45 and lower headers for each group, a down-comer from the mud drum to the lower header of each group, an upcomer from the upper header of each group, and a down-comer from each upper to each lower header, a header 50 common to the down-comers, a plurality of small tubes connecting said header to the

mud drum, a header common to the upcomers, and a plurality of small tubes connecting said header to an upper drum.

2. In combination, a boiler having steam and water space, a combustion chamber, a tubular screen for an upright wall thereof, the tubes of which are divided into groups, upper and lower headers for each group, a downcomer leading from the boiler to the lower header of each group, an upcomer from the upper header of each group, a header common to the downcomers, a plurality of small tubes connecting said header to the boiler, a header common to the upcomers, and a plurality of small tubes connecting said header to the boiler.

3. In combination, a boiler having upper steam and water drums and a mud drum, a bank of upcomer tubes connecting said mud drum with a steam and water drum, certain of the tubes being subject to radiant heat, a bank of downcomer tubes connecting a second of the steam and water drums with the mud drum, means connecting the steam and water drums, a combustion chamber having tubular water walls defining a substantial portion of the combustion space and subject to radiant heat, and means connecting said water walls into the circulation of the boiler and arranged so that the delivery from tubes of the installation subject to radiant heat is divided between the steam and water drums.

4. In combination, a boiler having a pair of upper steam and water drums, and a lower mud drum and interconnecting tubes, a combustion chamber, boiler tubes for an upright wall of the combustion chamber, downcomer means from the mud drum to said boiler tubes, upcomer means from said boiler tubes to one of the upper drums, boiler tubes for another upright wall of the combustion chamber, a bottom screen for the combustion chamber, downcomer means from the mud drum to said bottom screen, and means connecting said bottom screen to said last mentioned boiler tubes, said last mentioned tubes being connected into the mud drum to deliver thereinto.

In testimony whereof I have hereunto signed my name.

ARNOLD RÜHR.
